UNITED STATES PATENT OFFICE.

HARRY HARVEY, OF SAN BENITO, TEXAS.

HANDLE-SECURING DEVICE.

Application filed October 25, 1923. Serial No. 670,675.

To all whom it may concern:

Be it known that HARRY HARVEY, a citizen of the United States, residing at San Benito, in the county of Cameron and State of Texas, has invented certain new and useful Improvements in Handle-Securing Devices, of which the following is a specification.

This invention relates to new and useful 10 improvements in a handle securing device and more particularly relates to an improvement over the handle securing device covered by Patent #1,196,683 obtained by me August 29, 1916.

15 The principal object of the present invention is to provide a means whereby the handle associated with the eye of any tool such as a hoe, axe, pick, will be secured therein in such a manner as to prevent any 20 possibility of the handle from becoming disengaged therefrom while in use, said means being furthermore of such a construction as to enable the same to be placed upon any 25 of the above mentioned tools without having to use any part of the tool in connection with the securing means.

A still further object of the invention is to provide a handle securing means which may be readily and easily placed in position 30 upon the tool and handle therefor and which is of such a construction whereby the same is detachably associated with the tool upon which it is used.

35 A further object of the invention is to provide a handle securing device which is simple in construction, strong and durable and further well adapted for the purposes for which it is designated.

40 Other objects and advantages of the invention will become apparent during the course of the following description.

In the accompanying drawings forming a part of this specification, and in which like numerals designate like parts throughout 45 the same,—

Figure 1 is a plan view showing my device in use.

Figure 2 is a front elevation of a hoe and handle therefor with my device in position 50 thereon.

Figure 3 is a detail view of the ring member.

In the drawings wherein for the purposes of illustration is shown the preferred embodiment of my invention, the numeral 1 55 designates the blade of a hoe which is pro-

vided with the integral socket 2 at its upper portion in the manner as clearly shown in the drawings and as is further well known in the art. The bore of the socket 2 tapers 60 smaller towards its rear end and the purpose of this arrangement is also well known in the art and may be further described as being provided to receive the similarly tapered portion of the handle 3.

65 The outer end of the handle 3 is adapted to extend slightly beyond the outer face of the hoe blade 1 and will fit snugly in the socket whereby the accidental displacement of the handle through the rear end of the 70 socket is prevented. It sometimes happens, however, in the use of a tool similar to that herein referred to that the handle will accidentally become loosened from its seated position within the socket and thereby necessitate having to force the larger end of 75 the handle back into the socket, thus causing a considerable loss of time and sometimes injuring the person using the tool.

In order to overcome this difficulty and to 80 furthermore enable any tool having a socket for the purpose of receiving a handle to be supported in a locked position upon the handle at all times, I provide a detachable handle securing means which comprises a 85 substantially elongated metallic plate such as is shown at 4 in the drawings and which is furthermore provided with an aperture adjacent each end thereof, designated by the numeral 5. Cooperating with this plate 4 is a ring-like member shown at 6 in the drawings and which is furthermore provided with an enlarged opening 7 which will conform to the outer configuration of 90 the handle 3 the same being provided with 95 diametrically opposed ears having apertures 7' therein which when the ring is in place upon the handle will register with the apertures 5 provided in the outer ends of the plate 4.

100 In use, the plate 4 is adapted to extend across the outer face of the enlarged end of the handle 3 and also across the outer face of the hoe blade 1, preferably across the intermediate portion of the outer edge of the socket and the ring will fit over the portion of the handle 3 adjacent the rear end of the socket and with the parts arranged as thus described suitable fastening means such as 105 bolts or the like, and as further shown at 8 in the drawings, are adapted to extend through the registering apertures in the 110

plate and ring, respectively, in such a manner as to have the heads of the bolts engaging the outer face of the plate and the threaded ends which extend through the apertures 7' of the ring 6, receiving on the outer ends thereof the locking nuts 9. The nuts 9 are tightened on the bolts 8 so as to draw the plate tight against the outer face of the enlarged end of the handle and also drawing the ring 6 up against the rear end of the socket, it being further understood that the bolts 8 will be tangential to the rear edge of the blade 1, as shown in Figs. 1 and 2 of the drawing.

In this manner the handle is securely held within the socket of the tool and the fastening means will in no way interfere with the proper use of the tool and furthermore will not necessitate the alteration of any part of the tool in order to permit the fastening means to be placed thereon. It will thus be seen that any type of tool having a socket thereon for receiving a handle will be adapted to support my fastening device in a simple and efficient manner and furthermore permit the same to be readily and easily placed in position thereon, it being understood that the fastening device is entirely separate and independent of either the handle or the tool with which it is associated, thus rendering the same detachable and ready for use at all times.

From the foregoing description of the construction of my improved device, it will be seen that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having thus described my invention what I claim is:

1. In a device of the class described, the combination with a tool head having a tapering socket, the one end of said socket be-

ing flush with the one face of the tool and a handle member having an enlarged tapering end adapted to fit within the tapering socket to permit the extreme end to extend a short distance beyond the last mentioned end of said socket; of means for removably securing the handle to the tool head comprising an elongated plate applied to the flat end of the extended portion of the tapered end of said handle in spaced relation to the tool head, the ends of said plate projecting beyond the periphery of said end of the handle and provided with apertures, a ring member applied to the handle and abutting the opposite end of the socket on the tool head, said ring member being provided with diametrically opposed ears having apertures therein adapted for registration with the apertures in said plate, tie bolts extending through the registering openings of said plate and ring having the heads thereof in abutment with the outer face of said plate and the threaded ends extended beyond the apertures in said ring, and nuts engaged with the threaded ends of said bolts and adapted to contact with the one face of said ears on the ring to secure the elements together, as and for the purposes described.

2. Means for securing the enlarged tapered end of a handle to an implement having a tapered socket formed thereon, the same consisting of an elongated plate bearing against the outer flat end of the tapered portion of the handle and disposed in spaced relation to the socket and implement, the ends of the plate projecting beyond the periphery of said handle and having apertures therein, a ring member applied to said handle and adapted to abut the peripheral edge of the opposite end of said socket, said ring member being provided with diametrically opposed apertures registering with the last mentioned apertures of said plate, and tie bolts engaged through the registering apertures of said plate and ring member, as and for the purposes described.

In testimony whereof I affix my signature.

HARRY HARVEY.
